PLUG-IN RELAY

Harold E. Seaton, Shelby, Ohio, assignor to The
Autocall Company, Shelby, Ohio, a corporation
of Ohio

Application July 28, 1948, Serial No. 41,029

10 Claims. (Cl. 200—87)

1

The present invention relates to an electrical relay.

One of the objects of the invention is to obtain an extremely high speed of operation. In this regard, a more specific object is to obtain higher operating speeds in a multiple contact type of relay having a considerable number of moving contacts, and having considerable contact pressure established between the moving and stationary contacts. The preferred embodiment of my invention herein disclosed is of this multiple contact, high pressure type. In my improved relay I obtain operating speeds as high as approximately 6 to 8 milliseconds (.006 to .008 second) or even higher, depending upon adjustments. The design of relay in which I obtain these operating speeds has six moving contact fingers, and maintains a contact pressure of at least thirty grams in its energized position and in its deenergized position.

This high speed operation is extremely important, or even essential, in certain situations, particularly exemplified in high speed calculating machines employing hundreds or thousands of these electro-mechanical relays and performing such operations as multiplications, divisions, additions, subtractions, and many other mathematical functions, at a rate of approximately 60 to 100 per second. The very fast operation is also very important in supervisory signaling systems, such as waterflow and sprinkler supervisory systems; also in the supervision and remote control of equipment in steam power plants, hydro-electric power plants, and the like.

Another object of the invention is to provide a relay which will have this high speed operation, and will also have an extremely long life without failure of operation, at least from the standpoint of multiplicity of operations. For example, my improved relay is designed to meet the requirement of 100 million complete cycles of operation without a failure, and the relay has met and exceeded this requirement in actual operation.

In attaining this high speed operation and long operating life, it becomes quite important to reduce the collection of dust upon the contact surfaces to an irreducible minimum. This also applies to the silver dust or metallic dust resulting from the wearing away of the contact surfaces themselves.

One of the features of my invention of particular benefit in minimizing the collection of dust on the contacts is the mounting of all of the contacts in vertical position, preferably side-by-side,

2

instead of being stacked on top of each other horizontally, as in conventional relays. Thus, ordinary dust and silver dust tend to gravitate off the vertical surfaces of these vertically disposed contacts. In this construction, the magnetic circuit and contact operating mechanism are arranged to extend horizontally rearwardly from this bank of vertically disposed movable contacts. The relay is made of more compact construction by virtue of this horizontal disposal of the magnetic circuit.

Another feature of the invention which is of pronounced benefit minimizing the collection of dust on the contacts is the fact that the relay is of the "window" type. The relay is adapted for panel or cubicle mounting, and the front of the relay carries an individual glass window directly in front of the vertically disposed bank of movable and stationary contacts. This individual sight window helps prevent the collection of dust on the contacts by cooperating with the panel in closing off the front of the banks of relays. This individual sight window has the further advantages of enabling direct observation of the contacts and their operation to be had; and it also prevents external touching of the contacts.

Another object of the invention is to provide an improved plug-in or jack-connected type of relay construction. The movable contacts, stationary contacts and magnetic circuit all have mounting assembly upon a portable relay frame in the form of a small compact unit, which unit is adapted to have plug-in mounting in a separate socket frame which is secured to the mounting panel and is wired on the rear side of the panel entirely independently of the separate relay unit. All electrical connections to the separable relay unit are extended to terminal prongs which project from the relay unit and are adapted to have plug-in engagement in terminal sleeves or sockets provided in the plug-in mounting frame. The individual sight window for the relay unit is carried in the front of the separable relay frame. This plug-in mounting facilitates the operation of wiring the plug-in socket, and also enables different or substituted relay units to be plugged into and out of operative positions almost instantly.

Another feature of the invention resides in having the spring flexure of contact engagement occur substantially entirely within the movable transfer contacts, rather than in the stationary contacts. That is to say, the movable transfer contacts are capable of a certain amount of

overtravel in each direction of their motion, i. e. when moving rearwardly into engagement with the normally open stationary contacts or when moving forwardly into engagement with the normally closed stationary contacts. Upon engagement with either set of the stationary contacts, this overtravel is absorbed by flexure of the movable contact fingers in preference to flexure of the stationary contacts. This flexed condition of the movable contact fingers maintains the desired relatively high contact pressure during the entire time that the operating armature remains in either of its two positions.

In this regard, another feature of the invention resides in the provision of an improved contact pressure spring arrangement, entirely separate and apart from the contact fingers, for maintaining the armature and movable contact fingers in their de-energized position. A further feature supplementary thereto is the provision of improved means for adjusting the pressure of this contact pressure spring.

Another feature of the invention related to the above-described overtravel of the movable contact fingers is the provision of improved adjustable stop means for limiting the momentary overtravel of the armature when released from the energized position. This adjustable armature stop may be desirable in some instances so as to prevent overtravel and rebound of the armature causing the contacts to bounce or chatter in the de-energizing operation.

Another feature of the invention resides in the provision of improved adjustments for adjusting the positions of the electromagnet and of the armature relatively to the movable transfer contacts and relatively to each other.

My improved relay can be constructed of various types, such as (1) the ordinary single coil type; (2) the double coil type wherein one coil serves as a pick-up winding and the other as an electrical seal-in winding; and (3) the latching type wherein the contact actuating armature is mechanically latched in its energized position, and requires the energization of a separate unlatching coil for its release.

Other objects, features and advantages of the invention will appear from the following detail description of certain preferred embodiments of the invention. In the accompanying drawings illustrating such embodiments:

Figure 1 is a fragmentary front view of a mounting panel or cubicle in which my relays are mounted, and wherein Figure 1A shows a relay unit in its mounted position in the plug-in socket, and wherein Figure 1B shows the front face of the plug-in socket frame with the relay unit removed therefrom.

Figure 2 is a rear elevational view of the relay unit removed from its plug-in socket frame;

Figure 3 is a fragmentary view from the inside of the panel or cubicle showing the mounting of the socket frame in a substantially corresponding opening cut in the panel;

Figure 4 is a side view of the relay unit (partly in section) preparatory to being inserted into the socket frame;

Figure 22 is a side elevational view, partly in section, showing my invention embodied in a latching type of relay, and

Figure 23 is a plan view of this latter embodiment.

In Figure 1, I have shown a relay (Figure 1A), and a mounting socket for a relay (Figure 1B), mounted side-by-side in a vertical mounting panel, cubicle wall or the like which is indicated fragmentarily at P. In the case of a calculating machine of the relay type, such as I have referred to above, there would be hundreds, or possibly thousands, of these individual relays disposed in closely spaced rows and columns in these vertical mounting panels or cubicle walls P. Figure 1A is a front elevational view of one of the relay units R mounted in its normal position in the mounting panel. Figure 1B illustrates the relay unit R removed, this figure showing in front elevation the plug-in mounting socket S which is fixedly secured in the mounting panel P for each of the relay units R.

Referring first to the relay unit R, this comprises a rectangular front frame 30 composed of insulating material. As shown in Figure 4, this frame 30 comprises front and rear frame sections 30a and 30b, between which are clamped

the banks or rows of movable contacts and co-operating stationary contacts. Formed within these front and rear frame sections 36a and 36b are rectangular openings 31 which define a sight opening extending entirely through the mounting frame 38 from front to back. Mounted in the front edge of this opening 31 is a pane of glass or transparent plastic material 32 which forms a sight window through which can be observed the condition and operation of the relay contacts. This pane of glass is removably held against a recessed retaining shoulder in the front section 36a by retaining clips 34 secured to the mounting frame 38 by screws 35. The mounting of the relay unit R in the socket frame S establishes a dust-tight joint between the relay unit and the panel P, and the glass sight window 32 establishes a dust-tight closure over the front of the sight opening 31, and hence dust cannot reach the contacts from the front of the relay. Where the relays are mounted on the vertical panels or cubicles, the interiors of these cubicles are usually made dust-tight as well.

Clamped between the front and rear halves 36a and 36b of the contact mounting frame 38 are the bank of movable contacts 37, the bank of stationary front contacts 38, and the bank of stationary rear contacts 39 (Figure 4). These three banks of contacts extend vertically in the sight window opening 31, with the contact points of all three banks visible through the window pane 32. The upper ends of the movable contacts 37 have electrical connection with a bank of plug-in prongs 37a projecting rearwardly from the frame 38 adjacent to its upper edge (Figure 4). Similarly, the bank of front stationary contacts 38 (which are the normally closed contacts in the de-energized condition of the relay) are provided with plug-in prongs 38a which project in a bank from the rear of the frame 38 adjacent to its lower edge. Similarly, the rear bank of stationary contacts 39 (which are the normally open contacts in the de-energized condition of the relay) are provided with plug-in prongs 39a which project rearwardly from the frame 38 above the bank of prongs 38a. These three banks of rearwardly projecting plug-in prongs 37a, 38a and 39a are adapted for reception in plug-in terminal sleeves 41, 42 and 43, respectively, mounted in horizontal rows in the socket frame S (Fig. 1B and Fig. 5).

The contact mounting frame 38, together with its contacts 37, 38 and 39, and its plug-in prongs 37a, 38a and 39a, constitute one sub-assembly of the relay unit R. Projecting rearwardly from this sub-assembly is another sub-assembly comprising the electromagnet 45 and its armature 46. This electromagnet and armature sub-assembly is carried between upper and lower mounting brackets 47 and 48 which are provided with laterally projecting attaching ears 47a and 48a. These attaching ears are set into recesses formed in the rear frame section 36b, and are secured to the assembled frame by screws 49 passing through from the front of the frame and threading into tapped holes in the attaching ears 47a and 48a. I shall describe the details of the electromagnet and armature sub-assembly after describing the socket frame S and the details of assembling the contacts in the relay frame 38.

Referring now to the socket frame S, it will be seen from Figure 5 that it is provided with a large rectangular opening 51 through which passes the electromagnet 45, armature 46 and the upper and lower mounting brackets 47 and

52. This rearwardly projecting sub-assembly is adapted to pass through the opening 51 so that it lies substantially entirely on the rear side of the socket frame S. Formed along the top and bottom edges of the frame S are flanges or lips 52, 52 which are adapted to abut against the front side of the mounting panel P. Extending across the upper portion of the frame S is a relatively thick portion 53 in which is mounted the row of terminal sleeves 41 for receiving the plug-in prongs 37a. Similarly, extending across the lower portion of the socket frame is a thick portion 54 in which are mounted the two rows of terminal sleeves 43 and 42 for receiving the plug-in prongs 38a and 39a. Figure 3 illustrates the preferred shape of the opening 55 which is punched out in the panel P for mounting the socket frame S. This opening 55 conforms to the top and bottom edges of the thickened portions 53 and 54, and intermediate these portions the opening 55 is formed with side flange portions 56 which overlie the side margins of the socket frame a sufficient distance to have threaded holes 57 formed therein into which thread mounting screws 58. As shown in Figure 5, the mounting screws 58 pass through the socket frame from the front and thus securely hold the socket frame in its fixed position in the opening 55 of the panel. The terminal sleeves 41, 42 and 43 are preferably of the split eyelet type, such being a well known construction. The opening for each terminal sleeve or eyelet is formed with a recessed slot 61 at its rear end, so as to provide a cavity for the expansion of the sides of the terminal sleeves when flattened in position. The expansion of the terminal sleeve into the slot 61 prevents the terminal from turning, which is an advantage in manufacture, and in the connecting and soldering of the wires to the terminal. Holes are punched in the flattened terminal sleeve to hold and clamp the wire before soldering. Such wires are not shown, but it will be understood that they are soldered to the rear ends of the terminals or eyelets 41, 42 and 43 on the inner or back side of the panel P. The socket frame S is composed of any suitable insulating material, typically represented by a phenolic condensation product, such as Bakelite.

As previously described, the mounting of the relay unit R in the socket frame S establishes a dust-tight joint between the relay unit and the panel P, and the glass sight window 32 establishes a dust-tight closure over the front of the sight opening 31, so that dust cannot reach the relay contacts from the front of the relay. More specifically, the socket frame S has sealing surfaces along the top and bottom flanges 52 and along the sides overlying the panel flanges 56 (Figure 3), which sealing surfaces on the socket frame abut coacting sealing surfaces on the outer side of the panel P, thereby forming a dust-tight joint between the mounting frame and the panel around the edge of the panel opening 55. Similarly, the back surface 62 of the rear relay frame section 36b and the front surface 63 of the socket frame S abut together as coacting sealing surfaces, thereby forming a dust-tight joint between the relay unit R and the socket frame S. When the relay unit R is plugged into the socket frame S, the weight of the relay unit R, and other stresses incident to the support of such unit, are borne by the engagement of the plug-in prongs 37a, 38a and 39a in the plug-in terminal sleeves 41, 42 and 43, and by the abutment of the back surface 62 of the relay frame section 36b against

the front surface 62 of the socket frame S, at the latter of the above described dust-tight joints. It will be seen that when the relay unit R is in this plugged-in position in the socket frame S, the electromagnet armature sub-assembly 45, 46, and particularly the electromagnet 45, extends entirely through the aligned holes in the socket frame and panel, so that it lies inwardly or rearwardly of the plane of the plug-in prongs and plug-in sockets and rearwardly of the two dust-tight joints, particularly of the separable dust-tight joint 62-63. Thus, the weight of the electromagnet 45 and the weight of the relay frame sections 38a and 38b tend to balance each other on opposite sides of the plane of support, which plane of support is defined approximately by the plane of the plug-in prongs and sockets and the plane of the separable dust-tight joint 62, 63. This substantially balanced relation avoids the possibility of any long continued vibration loosening the engagement of the plug-in prongs in their sockets or accidentally separating the dust-tight joint 62-63.

Referring to the more specific details of the relay contacts and the manner of their assembly within the contact mounting frame 30, Figure 7 is an inner elevational view of the front face of the rear frame section 38b, illustrating the first step in the operation of assembling the relay contacts. Mounted in appropriate recesses in the upper part of this rear frame section are the transfer contact terminals 37b to which are secured the movable transfer contacts 37. These terminals 37b have rearwardly bent upper ends which pass rearwardly through holes in the frame section 38b and constitute the upper bank of plug-in prongs 37a. I shall hereinafter describe the manner of securing the movable transfer contacts 37 to these terminals 37b.

Referring now to the lower part of the rear frame section 38b, it will be seen that a rectangular cavity 64 is formed in the lower portion of this frame section, and assembled in this cavity is the bank of stationary rear contacts 39. The lower ends of each of these rear contacts are provided with rearwardly bent extensions which pass through holes in the frame section and constitute the bank of plug-in prongs 39a.

Disposed in cavities along the side portions of the frame section 38b are upper and lower coil terminals 65 and 66, which are provided for the purpose of establishing electrical connection with the one or more coils of the electromagnet 45. The upper ends of the terminals 65 are provided with plug-in prongs 65a (Figure 6) disposed at opposite ends of the bank of plug-in prongs 37a. The lower ends of the lower terminals 66 are likewise provided with plug-in prongs 66a (Figure 2), disposed at opposite ends of the bank of plug-in terminals 39a. The adjacent inner ends of these coil terminals 65 and 66 are provided with rearwardly projecting tabs 65b and 66b which extend back through the opening 31 for establishing soldered connection with the terminals of the electromagnet coil or coils.

The next step in the assembly operation is to set into the rectangular cavity 64 a contact spacing block 68, shown in detail in Figures 8 and 9. This block, composed of insulation, has a rear bank of cavities 69 for fitting over the stationary rear contacts 39. The front face of this block has a similar set of cavities 71 for receiving the bank of stationary front contacts 38. After the placing of the block 68 over the rear contacts 39, the front contacts 38 are then assembled in their

5 cavities 71 in the front face of the block, as shown in Figure 10. The lower ends of these front contacts 38 have rearwardly bent portions which pass through holes in the spacing block and in the rear frame section and constitute the lower bank of plug-in prongs 38a. The parts are now in the assembled relation illustrated in Figure 11. The front cover section 30a of the frame 30 can now be assembled over this assembled relation of rear frame section and stationary contacts. As will be later described, this may take place either before or after the mounting of the movable transfer contacts 37, depending upon the construction of these transfer contacts or any other preferred sequence of operation.

Figures 14 and 15 illustrate two different types of mounting for these movable transfer contacts. In Figure 14 the downwardly projecting terminal portion 37b is formed with a notch or slot 37c extending across the entire width of its front face. Formed in the upper portion of the contact finger 37 is an offset hump or rib 37d extending across the width of the finger and adapted for snug fitting reception within the slot or notch 37c. The hump or rib 37d is forced into firm pressure engagement within the notch 37c by the pressure of drawing the front frame section 38a back into tight fitting engagement against the rear frame section 38b. The horizontal width of bearing engagement between the rib and the notch firmly hold the contact finger 37 against sidewise swiveling movement relatively to the terminal portion 37b.

In the modified contact finger mounting illustrated in Figure 15, the terminal portion 37b is extended down lower, so as to project into the rectangular opening 31 of the mounting frame. Formed in this downwardly projecting portion is a threaded hole 37e. In this case, the contact finger 37 is provided with an aperture 37f adapted to receive the attaching screw 37g which passes through the aperture 37f and threads into the tapped hole 37e. These mounting screws 37g are all accessible adjacent the upper edge of the opening 31, before the window pane 37 is inserted in place. The entire bank of the six movable transfer contacts 37 move as a unit into and out of engagement with the front and rear stationary contacts 38 and 39. In the de-energized condition of the relay, spring pressure acting against the armature holds the transfer contacts 37 pressed forwardly against stationary front contacts 38. Upon energization of the electromagnet, the transfer contacts 37 are pulled rearwardly out of engagement with the front contacts 38 and into engagement with the rear contacts 39. Attention is directed to the ridged formation along the top of the contact spacing block 68 for the purpose of deflecting contact dust and also for the purpose of increasing surface gap length between contacts. As viewed in Figure 4, a ridge 72 projects upwardly from the top of the block 68 between each companion pair of front and rear contacts 38 and 39. Thus, contact dust occurring from the wear of the contact points is deflected forwardly and rearwardly by this ridge as it falls down upon the spacing block. This ridge or barrier 72 creates a longer insulating path between the contacts 38 and 39. When a relay is required to operate approximately 100 million complete cycles without failure, it follows that there is a natural wearing away of the contact silver that causes a fine dust to collect on the spacing block 68. This dust, if allowed to collect on a flat horizontal surface, would in time

become heavy enough to provide an electrical path between the contacts 38 and 39, and a flash-over could occur over this path when a highly inductive circuit is de-energized. When this flash-over occurs, a carbonized path is burned into the surface of the spacing block, and serious trouble is the result. The longitudinal barrier ridge 72 forms part of a deep well around each contact. Cooperating with this longitudinal ridge is a series of transverse ridges 73 which extend from front to rear of the spacing block 68 (Figures 8-10) between companion pairs of front and rear contacts 38 and 39. Thus, the longitudinal and transverse barrier ridges 72 and 73 form a deep well around each contact, so that the silver dust wearing away from the contacts, or any other form of metallic material, slides down the angle of the barrier into the well around each contact, where it can do no harm. Therefore, a longer, cleaner and better insulating path is maintained between all of the stationary contacts. In addition to eliminating the objectionable dust condition, it will be noted that any foreign metallic chips or particles that may find their way between the contacts will lodge in the wells and become stationary, thereby avoiding the possibility of their bouncing or moving around from one contact to another, as is very likely to be the case when free to move across a flat surface.

The front cover section 29a is adapted to be secured to the rear section 29b of the frame by screws 75, 76 and 77. The upper row of screws 75 pass through both frame sections and thread into tapped holes in a metallic anchoring bar 78 recessed into the back side of the rear frame plate 29b. The screws 76 likewise pass through both frame sections and thread into tapped holes in a similar metallic anchoring bar 79 recessed into the back of the rear frame section. The lower corner screws 77 thread into nuts 81 recessed into the back of the rear frame section. The front face of the socket frame S is formed with molded depressions 82 in line with each of these clamping screws so as to receive any portion of one of these screws which might project beyond the rear face of the frame 38. The screws are all preferably of the Phillips or Reed and Prince type. The front and rear frame sections 29a and 29b and the contact spacing block 68 are composed of any suitable insulating material, such as Bakelite.

Referring now to the details of the electromagnet and armature sub-assembly 45, 46, the electromagnet coil 46a (Figure 19) is wound upon a magnetic core 84 which is preferably of flat rectangular cross section, with its larger dimension disposed horizontally. Embracing the coil and core is a U-shaped magnetic frame member 85. The vertical web portion of this U-shaped member is secured to the rear end of the core 84 by screws 85 (Figure 2), and the two legs 85a of the U extend forwardly above and below the coil 46a and terminate substantially flush with the front end of the core 84, thereby completing the magnetic circuit from the rear end of the core forwardly to the armature 46. A central opening 87 extends through the core for receiving the armature return spring 88, as I shall later describe. The U-shaped frame member 85 is mounted for fore and aft sliding adjustment between the upper and lower supporting brackets 47 and 48. As shown in Figures 6 and 16, a pair of screws 89 pass down through the top bracket 47 and screw into threaded holes in the mag-

netic frame member 85, and a similar pair of screws 89a (Figure 17) extend up through the bottom bracket 48 and screw into threaded holes in the lower leg of this frame member. In both instances, the screws 89 and 89a pass through elongated slots 90 formed in the brackets 47 and 48, which slots permit the frame member 85, together with the coil 46a and core 84 to be shifted longitudinally toward and away from the movable transfer contacts 37, and also to be shifted laterally, for the purpose of making any desired adjustments of the relative positions of the movable contact fingers and electromagnet-armature sub-assembly.

The armature 46 is provided at its upper end with rearwardly extending pivot lugs or ears 91 in which are preferably mounted self-lubricating oil retaining bearings 92. A pivot shaft 93 extends transversely through these bearings, and the intermediate portion of this shaft is mounted on the U-shaped frame member 85 in the manner illustrated in Figures 16 and 18. Mounted on the top of the frame leg 85a is an armature supporting bracket 94 having upwardly projecting end flanges 94a provided with notches 94b for receiving the pivot shaft 93. The horizontal web portion of the bracket 94 is provided with a pair of laterally spaced slots 94d adapted to receive the anchoring screws 95 which pass down through these slots and thread into tapped holes in the upper leg portion 85a of magnet frame 85. The pivot shaft 93 is retained in the notches 94b by a retaining clip 96 comprising a cross bar portion 96a and two forwardly extending legs 96b at the ends thereof. Screws 97 pass down through the leg portions 96b and thread into tapped holes in the flange portions 94a of mounting bracket 94. The under side of each retaining leg 96b is formed with an upward and rearward slope 96c so that the downward pressure exerted by the retaining screws 97 tends to cam the pivot shaft 93 in a rearward direction, so as to hold the pivot shaft pressed against the rear edge of each mounting notch 94b. This camming or wedging action exerted upon the armature pivot shaft prevents the shaft from working back and forth in the notches as the armature operates. It will be seen that by loosening the screws 95 the armature mounting bracket 94 can be shifted forwardly or rearwardly so as to adjust the position of the armature relatively to the electromagnet core 84 and frame 85. Furthermore, this arrangement permits the armature 46, mounting bracket 94 and retaining clip 96 to be completely assembled as a sub-assembly, following which this sub-assembly can then be secured to the upper leg 85a of the electromagnet frame 85 by the introduction of the clamping screws 95 down through the slots 94d into the frame leg 85a.

Referring now to the manner in which the armature 46 transmits motion to the movable transfer contacts 37, this motion transmitting relation is established through a contact actuating bracket 101 which is secured to the outer face 65 of the armature 46. This bracket is composed of insulation, such as Bakelite, and has laterally spaced attaching ears 101a through which clamping screws 102 extend for threaded mounting in tapped holes in the armature 46 (Figure 17). A flange portion 101b (Figure 19) projects forwardly from this bracket, and formed in this flange portion at spaced intervals are slots 101c through which extend the movable contact fingers 37. Molded on the top side of the flange portion 101b are transversely spaced barrier ridges

101d which extend rearwardly between the slots **104c**. These barrier ridges establish a longer insulating path between the transfer contact fingers **37**, in the same manner that the barrier ridges **13** increase the length of the insulating path between adjacent stationary contacts **38**, **38** and **39**, **39**. It will be seen that the contact operating bracket **101** causes the entire bank of movable contacts **37** to be flexed forwardly and rearwardly simultaneously with the forward and rearward movement of the armature **46**.

Referring now to the armature return spring **88**, it will be seen from Figure 19 that the front end of this spring seats in a depression **104** formed in the back side of the armature **46**. The spring is preferably tapered with its smaller end at the front so as to avoid any possibility of the front portion of the spring having any frictional drag engagement against the sides of the opening **87** in the oscillatory motion of the armature. The rear end of the spring bears against a centering head **105** on the front end of an adjusting screw **106**. The screw threads outwardly through the tapped bore of a nut **107** which has a press fit to the desired depth within the opening **87**. The nut **107** is made of the self-locking type, such being a well known construction, by crimping therein a friction gland ring or retaining washer **108** which serves to frictionally hold the adjusting screw **106** in each of its adjusted positions within the nut **107**. It will be seen that the pressure of the spring **88** can be easily adjusted by inserting a screw driver into engagement with the kerf **109** in the end of the screw **106** and rotating it in the appropriate direction to increase or decrease the pressure of the spring. Figure 19 illustrates how the overtravel of the armature **46** in each direction of movement causes flexing of the movable contact fingers **37**, and thereby establishes the desired relatively high contact pressure and sliding or wiping action against both the front and back stationary contacts in the two positions of the armature. Normally, the spring **88** maintains each movable contact finger **37** flexed forwardly in the full line position illustrated in Figure 19, and when the relay is energized the retractive movement of the armature flexes these movable contact fingers rearwardly into the dotted line position. I preferably construct and adjust the relay so that contact pressures of at least 30 grams are obtained against both the front and back contacts **38** and **39**.

Referring now to the manner in which the transfer contact fingers **37** are assembled in the relay, these contact fingers are threaded up through the slots **101c** in the contact operating bracket **101**. The clamping or holding screws **49**, **75**, **76** and **77** are started but not tightened until after the transfer contacts have been located in their proper positions. After being threaded through the slots **101c**, the terminal ends of the contacts are then threaded in between the frames **30a** and **30b** until the silver tips of contacts **37** are positioned between the contact operating bracket **101** and the stationary front contacts **38**. It will be noted that due to the pressure of the armature spring **88**, the bracket **101** now extends out through the opening **31**. This brings the slots **101c** in bracket **101** nearly in line with the face of frame **30a**. Bracket **101** is then pressed inwardly until contacts **37** are positioned above and between stationary contacts **38** and **39**. Contacts **37** are then pulled back in between stationary contacts **38** and **39** to their normal operating positions and aligning the offset humps

31d with the slots **31c** in the parts **37a**, or aligning the holes **37f** with the tapped holes **37e** for applying the anchor screws **37g**. After this assembly operation, screws **49**, **75**, **76** and **77** are securely tightened. While this is the preferred manner of assembly of the transfer contacts **37**, it will be understood that the invention is not limited to this sequence or manner of assembly.

In Figure 20, I have illustrated a modified construction which has the two-fold feature of providing an adjustment for the armature spring pressure, and also of providing an adjustable stop for preventing overtravel of the armature. In this construction, the front end of the axial opening **87** is provided with an internal thread **111** into which screws the threaded front end of a stop adjusting sleeve **114**. The compression spring **88** is confined within the bore **115** of this sleeve, and the front end of said spring acts upon the head **116** of a motion transmitting thrust pin **117**. Such thrust pin extends outwardly through a reduced counterbore in the end of the adjustable stop sleeve **114** and has its front end bearing in a depression **104** formed in the back side of the armature **46**. A stop washer **119** of shock absorbing material, such as rubber, leather or the like, is seated in the bottom of the bore **115**, and the head **116** of the thrusting pin is normally pressed against this washer by the spring **88**. The rear end of the bore **115** is internally threaded at **121** for receiving a spring pressure adjusting plug **122** which screws forwardly in this thread and adjusts the pressure of the spring **88**. Screw driver kerfs **123** and **124** in the sleeve **114** and plug **122**, respectively, provide for independent adjustments of these two elements. As stated above, screwing the plug **122** forwardly or rearwardly provides for adjusting the pressure of the spring **88**. Screwing the stop sleeve **114** forwardly or rearwardly in the thread **111** provides for shifting the position of the stop washer **119** forwardly or rearwardly to avoid objectionable overtravel of the armature. In the spring return movement of the armature, the thrust pin **117** is brought to a stop with a cushioned impact by the cushioning stop washer **119** and this prevents bouncing of the armature in such spring return movement.

In Figure 21, I have illustrated another modified construction in which overtravel of the armature in its spring return movement is positively limited by a positive stop rod **126**. In this construction, the magnet core is provided with a front bore **87a** and a rear bore **87b** connected by a reduced counterbore **87c**. The spring **88** is confined in the front bore **87a** and bears against the back of the armature. The stop rod **126** extends through the armature and has a positive stop head **127** on its front end. A cushioning washer **128** of shock absorbing material is interposed between the head **127** and the front part of the armature. The stop rod **126** extends back through the reduced counterbore **87c** and has threaded engagement in a self-locking nut **129**. This nut is similar to the nut **107** of Figure 19 in that it is provided with a contained ring of resilient gripping material which causes the nut to frictionally bind upon the threaded rear portion of the stop rod **126**. A cushioning washer **131** of rubber or other shock absorbing material is confined between the nut **129** and the bottom of the bore **87b**. It will be seen that the rod **126** is adjustable to define the outer limit of travel of the armature in its spring return motion, and it will be seen that this outer limit of travel is

positively defined, but is cushioned by the cushioning washers 123 and 131 to avoid bounce of the armature.

As described in the fore part of this specification, the electromagnet may be of the single coil type or of the double coil type. When the electromagnet 45 is of the double coil type, one coil serves as the energizing winding for attracting the armature to its energized position, and the other coil functions as a sealing or lock-up coil which serves to electrically lock up the relay in its energized position by maintaining the electromagnetic attraction, even though the circuit through the energizing coil or pickup coil has been interrupted. When the electromagnet is of the single coil type, the terminals of this single coil are soldered to one pair of the terminal tabs 65b or 66b, and when the electromagnet is of the double coil type, the other coil has its terminals soldered to the other pair of these terminal tabs.

My improved relay can also be constructed of the latching type, such as I have shown in Figures 22 and 23. In this construction, the upper and lower mounting brackets 47 and 48 are made substantially longer so as to mount another electromagnet 45 and armature 46 directly in back of the main electromagnet 45 and main armature 46. This rear armature 46 constitutes a latch releasing electromagnet. The main armature 46 has a latching arm 147 secured thereto and extending rearwardly across the top of the upper mounting bracket 47. This latching arm 147 is provided at its front end with a downturned flange which is secured by screws 148 to the front side of the main armature 46, whereby a standard construction of electromagnet and armature sub-assembly 45, 46 can be used in this latching type of relay, the latching arm 147 being a mere attachment secured to the regular design of armature 46.

The sub-assembly 145, 146 can be made identical with the main sub-assembly 45, 46, except that this rear sub-assembly 145, 146 is mounted in inverted position with the armature hinge at the bottom. Secured to the upper swinging end of the armature 146 is a latching dog 149, this dog being a separate attachment adapted to be secured to the regular design of armature by the attaching screws 151. The latching dog 149 extends upwardly through a cut-out opening 152 punched out of the web of the upper mounting bracket 47. Punched down out of the end portion of the latching arm 147 is a lug 153 which functions as a stop lug for limiting the forward spring return movement of the latching armature 146. The parts are shown in the latched position of the relay. The main armature 46 has been moved into its rearward position by the energization of the electromagnet 45, and this has caused the latching arm 147 to swing upwardly to a position where the latching dog 149 can snap in under the end of the latch arm 147. Hence, the main armature 46 will remain in its rearward position, with the movable transfer contacts 37 engaging the rearward stationary contacts 38, even after the electromagnet 45 has been de-energized. This latched relation will remain until the releasing electromagnet 145 is energized, whereupon the latching armature 146 will be attracted rearwardly, thereby snapping the latching dog 149 out from under the rear end of the latching arm 147, and permitting the main armature 46 to swing forwardly to its normal retracted position. In all other respects, this latching type of relay shown in Figures 22 and 23 is

the same as the single coil and double coil types previously described in Figures 1 to 21, inclusive.

While I have illustrated and described what I regard to be the preferred embodiments of my invention, nevertheless it will be understood that such are merely exemplary and that numerous modifications and rearrangements may be made therein without departing from the essence of the invention.

10 I claim:

1. In a relay adapted for plug-in mounting in a panel, the combination of a mounting frame adapted to be secured to the panel, said mounting frame having an opening therein adapted to be aligned with an opening in the panel, a relay frame adapted to be mounted on said mounting frame, sealing surfaces establishing a dust-tight joint between said relay frame and said mounting frame, cooperating movable and stationary contacts carried by said relay frame in position to extend substantially parallel with the front face of the panel in the mounted position of the relay on the panel, plug-in sockets carried by one of said frames and cooperating plug-in prongs carried by the other of said frames for reception in said plug-in sockets, said prongs and sockets defining a plane of support for said relay frame extending substantially parallel to said panel, and an electromagnet and armature for actuating said movable contacts carried by said relay frame and extending rearwardly beyond said dust-tight joint and beyond said plane of support and through said openings in the mounting frame and panel in the mounted position of the relay on the panel.

2. In a relay adapted for panel mounting, the combination of a socket frame adapted to be secured to a panel, said socket frame having an opening therein adapted to be aligned with an opening in the panel, sealing surfaces establishing a dust-tight joint between said socket frame and said panel, a relay frame adapted to be mounted on said socket frame, sealing surfaces establishing a separable dust-tight joint between said relay frame and said socket frame, cooperating movable and stationary contacts carried by said relay frame in position to extend substantially parallel with the front face of the panel in the mounted position of the relay on the panel, an electro-magnet and an armature responsive thereto carried by said relay frame for actuating said movable contacts, plug-in prongs electrically connected with said contacts and with said electromagnet and projecting rearwardly from said relay frame, and plug-in sockets in said socket frame adapted to receive said plug-in prongs when said relay frame is mounted in said socket frame, said electromagnet extending rearwardly beyond both said dust-tight joints and through said openings in the socket frame and panel in the mounted position of the relay on the panel.

3. In a relay adapted for plug-in mounting in a panel, the combination of a mounting frame adapted to be secured to a panel, said mounting frame having an opening extending therethrough adapted to be aligned with an opening extending through the panel, a relay frame adapted to have plug-in mounting on said mounting frame, cooperating sealing surfaces on said relay frame and on said mounting frame establishing a separable dust-tight joint therebetween, cooperating movable and stationary contacts carried by said relay frame, a substantially dust-tight sight window in the front of said relay frame through

which said contacts can be inspected from the front side of the panel when the relay frame has its plugged-in mounting on said mounting frame, an electro-magnet and an armature responsive thereto for actuating said movable contacts carried by said relay frame, said electro-magnet and armature mechanism projecting in a rearward direction from said contacts and from said sight window and adapted to extend back through said aligned openings in the mounting frame and panel in the mounted position of the relay on the panel, and cooperating plug-in prongs and plug-in sockets carried by said two frames and adapted to have plug-in reception when said relay frame is mounted on said mounting frame, said electromagnet extending rearwardly of the plane of said plug-in prongs and sockets and rearwardly of the plane of said separable dust-tight joint in the mounted position of said relay on the panel.

4. In a relay of the class described adapted for plug-in mounting in a panel, the combination of a mounting frame adapted to be secured to a panel, said mounting frame having an opening extending therethrough adapted to be aligned with an opening extending through the panel, a relay frame adapted to have plug-in mounting on said mounting frame and comprising front and rear insulating frame sections, a sight window opening extending through said frame sections, a bank of movable transfer contacts secured between the upper portions of said frame sections and extending downwardly into said sight window, front and rear banks of stationary contacts secured between the lower portions of said frame sections and extending upwardly into said sight window on the front and rear sides of said transfer contacts, contact actuating means operatively connected with said movable transfer contacts and extending rearwardly therefrom, an armature arranged to operate said contact actuating means, an electromagnet secured to said rear frame section and projecting rearwardly therefrom for operating said armature, plug-in sockets carried by said mounting frame, and plug-in prongs projecting rearwardly from said rear relay frame section for reception in said plug-in sockets, said plug-in prongs and plug-in sockets defining a plane of support for said relay frame extending substantially parallel to said panel when said relay frame is plugged into said mounting frame, in which position said electromagnet extends through the aligned openings in said mounting frame and panel and rearwardly of said plane of support.

5. In a relay of the class described adapted for a plug-in mounting in a panel, the combination of a socket frame adapted to be secured to the panel, said socket frame having an opening extending therethrough adapted to be aligned with an opening extending through said panel, a relay frame composed of insulation comprising front and rear frame sections, a sight window extending through said frame sections, a transparent pane closing the front side of said sight window, a bank of movable transfer contacts secured between said front and rear relay frame sections and extending into said sight window, front and rear banks of stationary contacts secured between said front and rear relay frame sections and extending into said front window on the front and rear sides of said movable transfer contacts, a contact actuating bracket connected with said movable transfer contacts, said bracket projecting rearwardly from said

bank of transfer contacts, an armature arranged to actuate said bracket, an electro-magnet secured to the rear side of said relay frame and projecting substantially horizontally rearwardly therefrom, said electro-magnet operating said armature, plug-in prongs projecting rearwardly from said rear relay frame section and operatively connected with said contacts and with said electro-magnet, and plug-in sockets in said mounting frame adapted to receive said relay prongs, said electro-magnet extending rearwardly of the plane of said plug-in prongs and sockets and rearwardly through the aligned openings in said socket frame and in said panel in the mounted position of the relay on the panel, with said front and rear frame sections being the only part of said relay extending forwardly from said panel.

6. In a relay of the class described, the combination of an insulating relay frame comprising front and rear frame sections, a sight window extending through said frame sections, a bank of movable transfer contacts secured between said frame sections and extending into said sight window in one direction, front and rear banks of stationary contacts secured between said front and rear frame sections and extending into said sight window from another direction, a spacing block of insulating material disposed between said front and rear banks of stationary contacts, said latter contacts being disposed on the front and rear sides of said movable transfer contacts, an insulating bridge member operatively connected with said movable transfer contacts, an armature to which said bridge member is secured, an electro-magnet to which said armature responds, bracket means securing said electro-magnet to said rear frame section with the electro-magnet projecting rearwardly therefrom, plug-in prongs bent laterally from the ends of said transfer contacts and stationary contacts and projecting rearwardly from said rear frame section, and a mounting frame in which said relay frame is adapted to have plug-in mounting, and plug-in sockets in said mounting frame for receiving the plug-in prongs of said relay frame, said mounting frame having an opening therein through which said electromagnet is adapted to extend in the mounted position of said relay frame in said mounting frame, with said front and rear frame sections of the relay frame being the only parts of said relay extending forwardly from said mounting frame.

7. In a relay of the class described, the combination of a bank of movable contact fingers, a bank of stationary contacts cooperating with said movable contact fingers, a relay frame on which said movable contact fingers and stationary contacts are supported, an armature connected to actuate said contact fingers, an electromagnet for actuating said armature, said electromagnet comprising a magnetic frame, a mounting bracket on which said armature has pivotal mounting, first adjustable securing means for adjustably securing said armature mounting bracket to said magnetic frame of the electromagnet whereby the armature mounting bracket and armature can be adjusted relatively to said electromagnet and said magnetic frame, and second adjustable securing means for adjustably securing said magnetic frame of the electromagnet to said relay frame whereby said electromagnet and armature can be adjusted as a unit relatively to said movable contact fingers, said first adjustable securing means being carried

by said magnetic frame to move therewith in the adjustments of said magnetic frame effected by said second adjustable securing means.

8. In a relay adapted for mounting on a panel or the like, the combination of a relay frame, cooperating movable and stationary contacts carried by said relay frame in position to extend substantially parallel with the front face of the panel in the mounted position of the relay on the panel, an armature connected to actuate said movable contacts, an electro-magnet for actuating said armature, said electro-magnet comprising a magnetic frame, a mounting bracket on which said armature has pivotal mounting, adjustable securing means for adjustably securing said armature mounting bracket to said magnetic frame of the electro-magnet whereby the armature mounting bracket and armature can be adjusted relatively to said electro-magnet and said magnetic frame, and adjustable securing means for adjustably securing said magnetic frame of the electro-magnet to said relay frame whereby said electromagnet and armature can be adjusted as a unit relatively to said movable contact fingers, said first adjustable securing means being carried by said magnetic frame to move therewith in the adjustments of said magnetic frame effected by said second adjustable securing means.

9. In a plug-in type of relay adapted for panel mounting, the combination of a socket frame adapted to be secured to the panel, said socket frame having an opening extending therethrough adapted to be aligned with an opening extending through said panel, plug-in sockets provided in said socket frame, a plug-in relay comprising a relay frame carrying plug-in prongs adapted for reception in said plug-in sockets, stationary and movable contacts carried by said relay frame electrically connected with said plug-in prongs, and an electromagnet and an armature carried by said relay frame for actuating said movable contacts, said plug-in prongs and plug-in sockets defining a plane of support for the relay frame extending substantially parallel to said panel when the relay is plugged into said panel, in which position said electromagnet extends through the aligned openings in said socket frame and panel and rearwardly of said plane of support.

10. In a plug-in type of relay adapted for panel mounting, the combination of a socket frame adapted to be secured to the panel, said socket frame having an opening extending therethrough adapted to be aligned with an opening
